DESIGN FOR AN ELECTRIC WATER HEATER

Maurice W. Grober, New York, N. Y., assignor of
one-third to Louis B. London and one-third to
Louis Newland, both of New York, N. Y.

Application December 4, 1936, Serial No. 66,303

Term of patent 7 years

To all whom it may concern:

Be it known that I, Maurice W. Grober, a citizen
of the United States and residing at New York,
in the county of New York and State of New
York, have invented a new, original and orna-
mental Design for an Electric Water Heater, of
which the following is a specification, reference
being had to the accompanying drawing, forming
part thereof, and in which

Fig. 1 is a top plan view of an electric water
heater showing my new design.

Fig. 2 is a front elevation thereof.

Fig. 3 is an end elevation thereof, and,

Fig. 4 is a bottom plan view thereof.

I claim:

The ornamental design for an electric water
heater substantially as shown.

MAURICE W. GROBER.
